UNITED STATES PATENT OFFICE.

JOHN LEECH, OF BRIDGEPORT, CONNECTICUT, ASSIGNOR TO INTERNATIONAL SILVER COMPANY, OF BRIDGEPORT, CONNECTICUT, A CORPORATION OF NEW JERSEY.

DESIGN FOR A SPOON, FORK, OR SIMILAR ARTICLE.

53,075.

Specification for Design.

Patented Mar. 11, 1919.

Application filed January 10, 1919. Serial No. 270,594. Term of patent 7 years.

To all whom it may concern:

Be it known that I, JOHN LEECH, a citizen of the United States, residing at 1109 Central Ave., Bridgeport, county of Fairfield, State of Connecticut, have invented a new, original, and ornamental Design for a Spoon, Fork, or Similar Article, of which the following is a specification, reference being had to the accompanying drawing, forming a part thereof.

In the drawing, Figure 1 is a representation of a spoon embodying my novel design with an outline of a fork, indicated by dotted lines, and

Fig. 2 is a perspective view on an enlarged scale of the tip of the handle showing the back.

What I claim is—

The ornamental design for a spoon, fork, or similar article, substantially as shown.

In testimony whereof I affix my signature.

JOHN LEECH.
